UNITED STATES PATENT OFFICE.

ARTHUR T. BEACH AND HOWARD C. RUSS, OF NEW YORK, N. Y.

ROTARY PUMP.

1,002,023.

Specification of Letters Patent. Patented Aug. 29, 1911.

Application filed June 3, 1909. Serial No. 499,937.

To all whom it may concern:

Be it known that we, ARTHUR T. BEACH and HOWARD C. RUSS, both citizens of the United States of America, the former residing in New York, borough of Brooklyn, county of Kings, and State of New York, and the latter in New York, borough of Manhattan, county and State of New York, have invented certain new and useful Improvements in Rotary Pumps, of which the following is a specification.

This invention relates to rotary pumps especially rotary vacuum pumps for general use in the trade, the object of the invention being to render pumps of this kind more efficient in operation.

More particularly the invention relates to helical mill cuts provided in the cylinder at the inlet and outlet ports, to provide for even wear of the pistons and to prevent the injurious pinching of air that would otherwise take place at this point.

In the accompanying drawings, Figure 1 represents a side-elevation of our improved rotary pump, Fig. 2 is a vertical longitudinal section of the same on line 2, 2, Fig. 3, Fig. 3 is a vertical transverse section on line 3, 3, Fig. 1, Fig. 4 is a diagram illustrating the extra bore given to the interior of the cylinder for providing for the free motion of the gates, and Fig. 5 is a longitudinal vertical sectional view of the cylinder, the rotating drum being removed.

Similar letters of reference indicate corresponding parts throughout the several figures of the drawings.

Referring to the drawings, *a* represents a cylinder which is supported stationary on a suitable base-plate *a*¹ and which is tightly closed by heads *a*² in which are arranged the journal-bearings for the piston-shaft *s*, both bearings being provided with suitable stuffing-boxes. The shaft is supported eccentrically to the cylinder *a* and carries at the interior of the same a rotatable drum *p*, which rotates with the shaft, and which is located eccentrically to the cylinder, but forms tangential contact with the same at a point intermediately between the inlet and outlet channels. The drum *p* is provided with two or four recesses *b*¹ in which are guided radially sliding pistons *b* between each pair of which are interposed square diametrical rods *b*² which pass through round openings in the drum *p* and shaft *s*. The outer ends of the pistons *b* are provided

with rounded grooves for receiving semi-cylindrical steel packing-bars *d*, which are accurately fitted into said grooves so as to turn in the same as the drum is rotated. The faces of the packing bars *d* are slightly curved, corresponding to the interior curvature of the cylinder *a*, so as to form always intimate contact with the same. The recesses in the drum *p* are somewhat longer than the length of the pistons and their packing bars, so as to prevent any concussion between the inner ends of the pistons and the inner ends of the recesses during the rotation of the drum in the cylinder. The foregoing construction is clearly shown in Letters Patent No. 861,937, dated July 30, 1907, for an improved rotary engine, and therefore not claimed in this application.

For providing for the extreme length between the faces of the packing bars of each pair of pistons and for the tight fitting of said packing bars to the interior surface of the cylinder, the cylinder is first bored out to be a true cylinder and then the upper portion of the inner surface of the cylinder at each side of the point of contact of the cylinder and piston, is bored out sufficiently on an arc of a circle so as to provide accurately for the distance between the faces of the packing bars and produce thereby the proper fitting of the pistons to the interior surface of the cylinder and the proper suction and discharge of the air or other medium through the inlet and outlet channels. The bores at the upper part of the cylinder are clearly shown in diagram, Fig. 4, and extend across the entire width of the cylinder, the radius of each bore being equal to the radius of the cylinder. If these auxiliary bores should not be provided, then the faces of the pistons would not tightly fit against the interior surface of the cylinder. The total length between the faces of the pistons has to be equal to the diameter of the cylinder, as in shifting, owing to the eccentric position of the drum in the cylinder, the pistons would not otherwise be able to pass along the upper part of the cylinder, or at least not without a seriously impeding jamming action. By the provision of the bores, the free motion of the pistons in the cylinder is secured, combined with the tight fitting of the pistons to the same, and a very effective suction-action is thus obtained during the rotation of the piston. The pis-

tons are preferably made of aluminum so as to reduce the weight of the same, while the packing bars are made of steel so as to resist more effectively the wear on the same.

5 The diametrical rods of each pair of pistons are square in cross-section and pass sidewise of each other through the shaft and form with the round openings in the piston and shaft connecting channels between the 10 recesses b^1 of the gates, so that the air or other medium back of the pistons can freely pass from that piston which is compressing the air, to the piston opposite thereto, so that the pistons are balanced, for the reason 15 that the air or other medium which passes along the sides of the pistons exerts no back-pressure on the air which is distributed in the space formed around the diametrical rod and in the space formed in the recess at 20 the opposite side of the drum. By this arrangement the free motion of the pistons is permitted, and likewise the free rotary motion of the drum.

When the faces of the packing bars are 25 gradually worn off, the reduced thickness of the same, is compensated by inserting thin steel-plates n between the rear ends of the pistons and the adjacent ends of the diametrical rods between the pistons, the steel- 30 plates restoring the exact total length of the pistons and rods and keeping up the tight fitting of the pistons to the inner circumference of the cylinder. When the packing bars are worn down to such an extent that 35 they do not project any more beyond the outer edges of the pistons they have to be replaced by new packing-bars, after which the interposed steel-plates are removed until they are gradually called into use again by 40 the wearing off of the packing-bars.

The inlet and outlet channels o^1 are arranged in the upper part of the cylinder equidistantly from the point of contact of cylinder and drum. Along the inner surface 45 face of the cylinder are arranged helical mill-cuts a^x for the purpose of preventing the uneven wear and consequently the untight fitting of the packing bars. The faces of the packing bars pass transversely over the mill-

cuts and have therefore a uniform wear 50 over their entire faces. The mill-cuts are preferably confined to the bores at the upper portion of the cylinder where extra tightness is required for the suction action of the pistons and for preventing the pinching 55 or compressing of the air between the discharge and the contact-point of cylinder and drum. When reversing the motion of the pump, the outlet channel becomes the inlet and the inlet-channel becomes the outlet 60 channel, the mill-cuts on the opposite bore acting then in the same manner on the pistons and the air being compressed at the point before stated.

For the purpose of lubricating the drum-shaft and its journal-bearings an outwardly-inclined channel is arranged in the brass-bearing leading from the oil-receptacle to the surface of the shaft at the outer end of journal. This channel is provided in each 70 journal-bearing. Owing to the partial vacuum at the interior of the drum created by the pistons, a slight suction is exerted on the lubricating oil in inward direction, so that the entire surface of the journals is 75 effectively lubricated.

Having thus described our invention, we claim as new and desire to secure by Letters Patent:

A rotary pump comprising a cylinder 80 having separated inlet and discharge openings in the upper part thereof and narrow helical mill-cuts in its inner surface adjacent to said openings, a rotatable drum disposed eccentrically within said cylinder and 85 provided with diametrical recesses, and pistons movable within said recesses and contacting with the inner surface of the cylinder.

In testimony, that we claim the foregoing 90 as our invention, we have signed our names in presence of two subscribing witnesses.

ARTHUR T. BEACH.
HOWARD C. RUSS.
